(57) **CLAIM**

The ornamental design for a robot wire, as shown and described.

DESCRIPTION

FIG. 1 is an isometric view of the robot wire showing my new design;

FIG. 2 is an isometric view of thereof;

FIG. 3 is a front view elevation view thereof; the back elevation view is a mirror image of the front elevation view; FIG. 4 is a top plan view thereof;

FIG. 5 is a bottom plan view thereof; and,

FIG. 6 is a right side view thereof; the left side view is a mirror image of the right side view.

The broken lines illustrate environmental structure and form no part of the claimed design.
